No. 14,382.

Oct. 31 1883.

UNITED STATES PATENT OFFICE.

ARTHUR OSBORNE, OF HYDE PARK, MASSACHUSETTS, ASSIGNOR TO
WILLIAM H. JACKSON, OF NEW YORK, N. Y.

DESIGN FOR A FACING FOR A FIRE-PLACE.

SPECIFICATION forming part of Design No. 14,382, dated October 30, 1883.

Application filed August 3, 1883. Term of patent 7 years.

To all whom it may concern:

Be it known that I, ARTHUR OSBORNE, a citizen of Great Britain, residing at Hyde Park, county of Norfolk, State of Massachusetts, have invented and produced a new and original Design for the Facing or Frieze of a Fire-Place Casing, of which the following is a specification, reference being had to the accompanying drawing, forming part thereof.

10 The drawing represents a front elevation of my newly-designed facing for entablatures.

The distinguishing characteristic features of this new design, viewed in elevation, as shown, consist, first, in a row of wrought or 15 raised circular flowers arranged at equal distances apart on a recessed central molded panel, which, with an intervening serpentine belt, similar small flowers, like daisies, and an undulating vine, cover the panel; secondly, 20 two ideal Grecian heads in relief, male and female, facing toward each other, and respectively located at the ends of the floral panel. These wreathed medallion-heads, exhibiting the contour of faces in profile, are on tablets 25 with plane borders without moldings. Similar plane borders inclose the molded floral

panel, and also constitute the entire marginal border of the frieze or entablature. Between the marginal plane borders and the plane borders which inclose the tablets and floral panel the ornamentation represents two rows of pear-shaped fruit or leaves in relief; and at the crossings of the plane borders, at the corners of the medallion-tablets and of the floral panel square rosettes of four leaves are 35 interposed.

I claim as my invention—

1. The design for a fire-place facing or frieze herein shown and described, consisting of the central floral panel with the two medallion- 40 tablets at the ends thereof.

2. The design for a frieze or entablature of a fire-place casing herein shown and described, consisting of the central floral panel with the two medallion-heads and the inclosing-borders. 45

Witness my hand this 9th day of July, A. D. 1883.

ARTHUR OSBORNE.
